UNITED STATES PATENT OFFICE.

PAUL E. WEBB AND FRANK A. WEBB, OF PROTECTION, KANSAS.

CARBID-HOLDER REGISTER.

1,245,076.

Specification of Letters Patent.

Patented Oct. 30, 1917.

Application filed March 29, 1917. Serial No. 158,300.

To all whom it may concern:

Be it known that we, PAUL E. WEBB and FRANK A. WEBB, citizens of the United States, and residents of Protection, in the county of Comanche and State of Kansas, have invented a new and Improved Carbid-Holder Register, of which the following is a full, clear, and exact description.

This invention relates to artificial gas lighting apparatus and has particular reference to acetylene gas generators.

Among the objects of the invention is to provide a self contained generating device including a carbid holder having means for dispensing or delivering measured quantities of the carbid from time to time into the body of water at the bottom of the machine and provide means whereby the operator may readily observe at any time on the outside of the machine the amount of carbid retained in the holder.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical sectional view of our improvement showing the carbid holder filled and the parts in position corresponding to such condition; and

Fig. 2 is a horizontal sectional view of the same on the line 2—2.

Referring now more particularly to the drawings we show a generating apparatus comprising a receptacle 10 for the body of water 11 and having secured to the top 12 thereof an upwardly projecting dome for a gasometer 13. These parts are shown as of cylindrical form, but as to the design we do not wish to be unnecessarily restricted. We would state also that with respect to details of the generator, such as the means for controlling or delivering the gas and which have no immediate bearing upon the improvement described in detail, it will be understood that any suitable design or construction of machine may be resorted to.

Within the dome 13 is arranged a guide

shown in the form of a hollow cylinder 14. The upper edge of this cylinder is fitted with a ring 15 and the lower end constitutes an outwardly projecting foot or flange 16 through which it is secured to the cover 12 of the base. The cover just referred to is open at 12' in its center beneath the guide.

17 indicates an upright standard or bracket secured as by bolts or rivets 18 upon the inner surface of the guide cylinder 14 adjacent to the lower end of the same. This bracket includes a guide lug 19 having a vertical eye at its upper end and at its lower end it is provided with a pair of ears 20 having horizontally alined holes.

21 indicates a supporting bar fitted slidably in the guide 19 and carrying at its upper end a horizontal annular seat or ring 22 that is concentric with the guide cylinder. Beneath the supporting ring 22 is a lever 23 having an open ring shaped body substantially directly below the ring 22. One end of the lever 23 is pivoted at 24 between the ears 20, this constituting a fixed pivot. A short distance inwardly from the fixed pivot is another pivot 25 through which the supporting bar 21 is connected to the lever through a hub or knuckle 26. The opposite end of the lever from the fixed pivot is provided with a head 27 to which a coil spring 28 is connected at one end while the other end of the spring is adjustably connected through a threaded bolt 29 and nut 30 to a bracket 31 fixed upon the inner wall of the guide cylinder opposite the standard 17. This spring 28 tends to draw upwardly upon the free end of the lever 23 thereby tending to cause the elevation of the rod 21 and the supporting ring 22.

32 indicates the carbid holder, the same constituting a receptacle fitted loosely within the ring or rim 15 and having a central conical point 32' at its lower end seated in the annular seat or ring 22. To the lower end of this holder is secured any suitable measuring device 33 adapted to receive a predetermined quantity of carbid from the holder and deposit the same downwardly through the center of the annular body of the lever 23 into the water 11. The holder 32 and the weight of material carried thereby serves to extend the spring 28, the weight aforesaid acting through the rod 21, knuckle 26 and lever 23. With the spring 28 carefully made of reliable material it will

be understood that the lineal extension of the spring will be directly proportional to the weight of the contents of the carbide holder.

5 For the reliable observation of the condition of the carbide holder or the amount of material therein at any time, we provide on the outside of the machine a scale 34 graduated preferably from 0 to 100 or any suitable minor graduations. Coöperating with this scale 34 is an index 35 carried upon the upper end of the rod 36 extending along a vertical tube 37 extending through the cover 12 outside of the dome 13. The rod 36 extends downwardly into the water and is bent inwardly and thence upwardly into substantial U-shape and has its inner end pivotally connected at 38 to the lever head 27. Because of this direct connection between the rod and the lever the extent of movement of the lever incident to the depression thereof by the weight or the elevation thereof, due to the action of the spring 28 when the weight is relieved, will be indicated directly by the index 35 upon the scale 34. As indicated the lever is supplied with 100 pounds of carbide which fact is indicated directly at the scale. While the carbide may be dispensed from the holder as required, the index will move up proportionally and will always point directly to the figure representing the number of pounds remaining in the holder.

We claim:

35 1. In a device of the character set forth the combination with a receptacle for water and a hollow guide member projecting upwardly therefrom, of a bracket secured upon the inner surface of the guide member, a carbide holder fitted slidably in the upper end of the guide member, supporting means for the carbide holder comprising an annular seat through which the lower end of the carbide holder projects and also including a vertical bar fitted slidably in said bracket, a lever pivotally connected at one end to said bracket and having pivotal connection with the lower end of said bar, and means

connected to the free end of the lever to control its movement under the influence of the weight of the carbide holder and indicate the amount of such weight at any time. 50

2. In a device of the character set forth the combination with a receptacle for water having a cover with an open center and a hollow guide member surrounding said opening and extending upwardly therefrom, of a carbide holder guided for vertical movement in the upper end of the guide member and having a conical lower end arranged over the center of said opening, an annular supporting seat through which the conical end of the holder projects downwardly, a supporting bar rigidly secured to the annular seat, a vertical supporting bracket in which said bar is guided, a lever having one end connected to a fixed pivot to the lower end of said bracket, pivotal connections between the lower end of the bar and the lever adjacent to the fixed pivot, said lever including an annular body arranged below the annular seat and through the center of which the material from the holder is adapted to be delivered into the water, and means connected to the free end of the lever for controlling the movement thereof around said fixed pivot according to the weight of material in the holder and to directly indicate to the observer the amount of such weight. 70 75 80

3. In a carbide holder register the combination with a carbide holder and vertically movable supporting means therefor, of a lever connected with said supporting means adjacent to one end, a spring connected to the opposite end of the lever and tending to elevate the same and the holder, a U-shaped rod pivotally connected to the same end of the lever at the spring and extending in a direction opposite from the spring, a graduated scale and an index carried by the opposite end of the rod and coöperating with said scale to show directly the weight in said holder. 85 90
